ADJUSTABLE DISPENSER FOR ROLL TOWELS

Council A. Tucker, Glendale, Calif., assignor to Towlsaver, Inc., Los Angeles, Calif., a corporation of California

Filed Sept. 25, 1964, Ser. No. 81,877

Term of patent 14 years

(Cl. D4—3)

FIG. 1 is an isometric view of an adjustable dispenser for roll towels showing my new design;

FIG. 2 is a side elevational view, the paper roll shown in broken lines being included for illustrative purposes only;

FIG. 3 is a front elevational view;

FIG. 4 is a top plan view;

FIG. 5 is a rear elevational view; and

FIG. 6 is a bottom plan view.

I claim:

The ornamental design for an adjustable dispenser for roll towels, as shown and described.
